UNITED STATES PATENT OFFICE

108,257

DESIGN FOR A LADY'S HEADDRESS

Elizabeth Durrant Barber, Miami, Fla.

Application November 16, 1937, Serial No. 72,940

Term of patent 7 years

To all whom it may concern:

Be it known that I, Elizabeth Durrant Barber, a citizen of the United States, residing at Miami, in the county of Dade and State of Florida, have invented a new, original, and ornamental Design for a Lady's Head Dress, of which the following is a specification, reference being had to the accompanying drawing, forming part thereof.

I claim:

The ornamental design for a lady's head dress, as shown.

ELIZABETH DURRANT BARBER.
